(57) **CLAIM**

The ornamental design for a bounding box for a user interface for an image processing machine, as shown and described.

DESCRIPTION

FIG. 1 is a front view of a bounding box for a user interface for an image processing machine showing the design of the present invention; and,

FIG. 2 is a front view of a second embodiment thereof.

The broken line drawings of a user interface for an image processing machine in FIG. 1 and for a portion of a user interface for an image processing machine in FIG. 2 are for illustrative purposes only and form no part of the claimed design.
